UNITED STATES PATENT OFFICE.

WILLARD E. PARTRIDGE, OF DETROIT, MICHIGAN.

DESIGN FOR A CLOCK-CASE.

No. 37,643.

Specification for Design.

Patented Nov. 7, 1905.

Application filed September 30, 1905. Serial No. 280,845. Term of patent 3½ years.

To all whom it may concern:

Be it known that I, WILLARD E. PARTRIDGE, a citizen of the United States, residing at Detroit, in the county of Wayne and State of Michigan, have invented a new, original, and ornamental Design for a Clock-Case, as shown in the accompanying drawings, forming a part hereof.

In the drawings, Figure 1 is a front eleva-

tion, and Fig. 2 is a side elevation, of the clock-case.

I claim—

The ornamental design for a clock-case, as shown.

WILLARD E. PARTRIDGE.
